RAILWAY TRACK CIRCUIT

Oscar S. Field, Rochester, N. Y., assignor to
General Railway Signal Company, Rochester,
N. Y.

Application June 7, 1935, Serial No. 25,472
Renewed March 2, 1938

14 Claims. (Cl. 246—41)

This invention relates to railway track circuits and more particularly to means for maintaining a substantially constant energization of a track relay associated with a track circuit regardless of changes in inter-rail leakage current due to changes in track ballast resistance and also regardless of changes in potential of the source of energy for the track circuit. This application is an improvement over my prior application Ser. No. 722,934 filed April 28, 1934, and the common invention between these applications is claimed in said prior application.

In a normally energized track circuit, a track relay is maintained energized when the track section is unoccupied by current flowing from a track battery through the track rails in series, and it is desirable to adjust this track circuit current to a value which reliably attracts the armature of the track relay, and yet which is sufficiently low to permit a train offering a maximum of rail shunting resistance to reduce the energization of the track relay to a degree which reliably releases its armature. However it is found that when the track circuit current is adjusted to a value permitting proper operation under average condition of track ballast, the increased inter-rail leakage current caused by wet ballast may prevent attraction of the relay armature or the decreased leakage current caused by dry ballast may prevent the release of the relay armature in response to a train shunt. It is also found that abnormal loads, improper charging or the like may cause variations in the voltage of the track battery which act in a like manner to prevent proper track circuit operation.

In view of the above and other considerations, it is proposed in accordance with the present invention to provide means which operates automatically to maintain a substantially constant track relay energization regardless of changes in inter-rail leakage current while the track section is unoccupied. It is further proposed to automatically distinguish the increments or decrements of inter-rail potential obtaining during an unoccupied condition of the track section from the more intense or abrupt changes in track relay energization, whereby to allow changes in energization of the track relay in response to the application and removal of a train shunt and to prevent operation of the automatic regulating means throughout the time in which a train shunt exists on the track section.

Other objects of the present invention include the provision of apparatus in a track circuit regulating means having novel structural features

of rugged and simple design providing greater efficiency, sensitivity and reliability of operation and which are arranged for convenient manual adjustment to permit a greater flexibility of application.

Still other objects, purposes and characteristic features of the present invention will appear as the description thereof progresses, during which references will be made to the accompanying drawings, in which:

Fig. 1 shows in a diagrammatic and conventional manner a preferred form of the present invention as applied to a conventional railway track circuit with certain parts of the apparatus shown in section and other parts illustrated in an exploded relation to their structural supports.

Fig. 2 is a sectional elevational view of a portion of a device shown in Fig. 1.

Fig. 3 shows in a wholly diagrammatic manner a modified form of the present invention also applied to the conventional railway track circuit.

Fig. 4 shows in a diagrammatic manner a modification which may be made in either the track circuit of Fig. 1 or Fig. 3.

Fig. 5 is a graphic illustration of the operating characteristics of typical track circuits employing the present invention and compared to the usual characteristics of conventional track circuits.

Referring to Fig. 1 of the drawings, a section of track rails 4 is shown divided from the adjacent track by insulating joints 5 to form a conventional insulated track section. A track relay TR of the type usually employed to control block signals is shown connected across one end of this track section and is normally energized from a suitable source of energy such as a storage battery B provided at the other end of the track section. A manually adjustable resistor 6 is employed in series with the battery B in accordance with the usual practice, and in the present arrangement, a resistor R is also included in series with battery B, which resistance R is provided with a movable arm 7 arranged to shunt out various portions thereof as will later be described in detail.

In the present system, the resistance inserted into the track circuit by the resistor R is automatically varied by an electro-magnetic means under the control of a relay which is diagrammatically illustrated as comprising a magnetic core 10 actuating a pivoted armature 11, the core 10 carrying windings 12 connected across the track rails 4 as shown. A movable contact 14 is attached to the armature 11 by an insulating

- block 15 and a compression spring 16 is provided to exert an upward biasing force opposing the normal gravitational bias on the armature 11, which force is manually adjustable by a screw 17.
- 5 A spring 18 is also provided to exert a downward biasing force on the armature 11 in opposition to the biasing force of spring 16, and the force of spring 18 is likewise manually adjustable by a screw 19.
- 10 The track circuit is adjusted by positioning the manually variable resistor 6 so that a desired energization of track relay TR is produced which obviously causes a definite upward attraction of armature 11 which has a substantially constant 15 relation to the degree of energization of the track relay inasmuch as the windings 12 are virtually in multiple with the track relay TR. The biasing forces of springs 16 and 18 are then adjusted so that the contact 14 is positioned mid-way between an upper adjustable fixed contact 20 and a lower fixed contact 21. In other words, the control relay is adjusted so that the force exerted by spring 18 plus the gravitational bias of armature 11 counter-balances the upward force of 25 spring 16 plus the upward magnetic attraction of armature 11 when a predetermined current flows in windings 12.

The lower fixed contact 21 cooperating with the movable contact 14 is illustrated as a pivoted arm biased upwardly by a compression spring 22 to engage a fixed contact 24, the compression spring 22 being adjustable by a screw 23. This arrangement permits the upward biasing force of spring 22 to be so adjusted that a slight 35 decrease in the energization of windings 12 causes a slight downward movement of armature 11 which engages contact 14 with the pivoted contact arm 21, but the force of this downward movement of contact 14 is not sufficient to disengage the arm 21 from the contact 24. However when the energization of the windings 12 is abruptly decreased, such as is effected by a train shunt, the downward force of armature 11 is sufficient to move the pivoted contact 21 out of engagement with the fixed contact 24.

45 The electro-magnetic means employed in the present system to actuate the arm 7 of the variable resistor R comprises three vertical parallel magnetic cores 27, 28 and 29 which extend through an insulating top plate 30 with their lower ends terminating in enlarged pole faces and having respective nuts 31 threaded thereon, whereby they are clamped on the top plate 30. The upper ends of the cores 27, 28 and 29 50 are jointed by a magnetic strip 32 clamped thereto by bolts 33, and the two outer cores 27 and 29 are provided with windings 35 and 36 respectively which are selectively energized in accordance with the position of contact 14 of the control 55 relay as will be fully described hereinafter.

The pole face at the end of the center core 28 is shaped to present a concave lower surface which is separated by a small air-gap from a solid magnetic cylinder 40 removably attached to a shaft 41 by means not shown herein. The shaft 41 is rotatably carried by a non-magnetic hanger member 42 which is suitably attached to the top plate 30, which member 42 is shown in Fig. 2 but has been omitted from Fig. 1. One end of the shaft 41 carries a pinion gear 43 suitably attached thereto as shown in Fig. 2 and indicated by dotted lines in Fig. 1, which pinion operates a sector 46 riveted to a shaft 47, the shaft 47 being 75 rotatably carried by a downwardly extending

arm 48 which may be integral with the hanger member 42.

Two armatures 58 and 59 are arranged as shown in Fig. 1 to magnetically coat with the cylinder 40 and the pole faces of cores 27 and 28 respectively. These armatures are each shaped to present a flat upper horizontal surface coacting with their respective pole faces while a downwardly extending portion is shaped to conform with the curvature of opposite sides of the cylinder 40, and the extreme lower ends of the armature 58 and 59 are pivotably attached to side members 61 and 62 by pivot pins 60. The side members 61 and 62 are rotatably carried on the shaft 41 at opposite ends of the cylinder 40, and horizontal extending ends thereof (one end being broken away in Fig. 1) carry cross rods 63 extending beneath the horizontal portion of each of the armatures 58 and 59, which cross rod 63 carries an upwardly extending screw 64 threaded therethrough whereby to adjustably limit the downward travel of armature 58 and 59.

The side armature carrying members 61 and 62 are biased to a center position by two oppositely disposed spring strips 70 carried by the hanger member 42 and shaped to normally engage opposite sides of a centering pin 72 fixed to the hanger member 42, to extend downwardly to also engage opposite sides of an operating pin 73 attached to the armature carrying member 61 and extending through a clearance slot in the hanger member 42. Two downwardly extending contact fingers 75 and 76 are clamped to the hanger member 42 by screws 77 which also hold the centering springs 70, the fingers 75 and 76 being insulated therefrom by insulating spacers 78 and 79. The contact finger 76 is provided with a contact 80 which is engaged by the end of a contact screw 81 threaded through the contact finger 76 when the armature carrying member 61 is in its center position. The lower ends of the centering springs 70 carry insulating blocks 79 suitably attached thereto which engage contact fingers 75 or 76 to separate contacts 80 and 81 when either of the springs 70 are moved away from the centering pin 72 by a clockwise or counter-clockwise rotation of the armature carrying member 61 about shaft 41.

40 The armatures 58 and 59 are each provided with an inwardly extending metal strip 66 held thereto by screws 68, the strip 66 of armature 58 being arranged to coat with notches in a peripheral ring 68 held in an annular groove in one end of the cylinder 40, while the strip 65 of armature 59 is arranged to coat with a second ring 68 similarly held on the other end of the cylinder 40 and having teeth oppositely arranged to the teeth of the first ring.

45 It may now be seen that energization of the winding 35 around the core 27 produces a flux 60 therein which flows through the center core 28, through the magnetic cylinder 40 and through armature 58, thereby first attracting the lower portion of armature 58 toward the cylinder 40 to engage the strip 66 with the teeth of the associated ring 68 and then attracting the outer end of armature 58 upwardly toward the pole face of core 27 which rotates the cylinder 40 in a clockwise direction. It will also be clear that the energization of winding 36 will in a similar 65 manner first attract armature 59 toward the cylinder 40 thereby engaging its strip 65 with the teeth of the ring on the other side of the cylinder 40 and the following upward travel of the outer end of armature 59 causes a rotation of 70 75

the cylinder 40 in a counter-clockwise direction. During the return travel of armatures 58 and 59, the initial movement is away from the cylinder 40 thereby withdrawing the strip 88 from the 5 teeth of the associated ring 88 so that the following downward movement does not rotate the cylinder 40.

During the above operation of either armature 58 or 59, the pin 13 is operated either to the 10 left or to the right which disengages contact 80 from contact 81 as previously described which opens a common portion of the energizing circuit for both coil 35 and coil 36 as will be obvious from the circuit arrangement shown in Fig.

15 1. In order to permit the armatures 58 and 59 to complete their travel after the energization of their associated coils is thus interrupted, a sleeve 14 of non-magnetic current conducting material is provided around the center core 28 20 which acts in the usual manner to retard any change in flux value therethrough. It will then be clear that after the energizing circuit for coils 35 or 36 is interrupted by the initial movement of armature 58 or 59, the flux value in the magnetic structure decreases slowly and continues to attract the armature which, together with the momentum imparted to the armature during the energization of its associated coil, is effective to complete its upward travel.

30 When the attracted armature has completed its upward travel, the flux in the magnetic circuit has decreased to a value permitting the associated biasing spring 10 to return the armature assembly to its center position. It is of course 35 obvious that the energizing circuit for coil 35 or 36 is again completed through contacts 80 and 81 before the armature assembly reaches its center position, but the sleeve 14 is again effective to retard the building up of a flux in the magnetic 40 structure to a value which is sufficient to overcome the biasing force of springs 10 until the armature assembly has reached a center position.

It may now be seen that the energization of either coil 35 or 36 attracts the associated armature upwardly whereupon a common portion of the energizing circuit for both coils is interrupted allowing the attracted armature to return to its original position after which it is again attracted and released as before, and this operation of one 45 of the armatures 58 or 59 continues as long as coil 35 or 36 is selected and energized by its external control circuit. In other words, the energization of coil 35 causes an oscillating motion of armature 58 which imparts intermittent rotation to cylinder 40 in a clockwise direction, while the energization of coil 36 causes an oscillation of armature 59 which imparts intermittent rotation to cylinder 40 in a counter-clockwise direction.

The specific contact arrangement illustrated for 60 the purpose of causing oscillatory motion of the armature assembly has been selected merely because of its simplicity, and it is desired to be understood that other contact arrangements may be employed. For example, a contact arrangement 65 having an asymmetric operation may be provided to maintain the coil energizing circuit closed during the major part of the upward armature travel but to hold the circuit open during the major part of the return travel.

70 The arm 7 which coats with the resistance wire R is shown in Fig. 2 as made up of two spring strips having the upper ends thereof separated to form a bifurcation contacting with opposite sides of the resistance wire R which may be wound 75 around a suitable insulating strip 88 having an

oval cross section as illustrated. The ends of the resistance wire R are anchored to terminal screws 85, and the insulating strip 88 is mounted beneath the top plate 30 by suitable brackets 84. The lower end of the arm 7 is suitably attached to an 5 insulating member 49 which is in turn mounted upon the sector 46 by screws 80 and spacers 81. It will then be clear that a clockwise rotation of cylinder 40 as effected by energization of winding 35 rotates the sector 46 in a counter-clockwise 10 direction through pinion gear 43, thereby moving the arm 7 nearer to the left-hand end of resistance wire R, and conversely a counter-clockwise rotation of cylinder 40 as effected by the energization of winding 36 rotates the sector 46 15 in a clockwise direction to move the arm 7 nearer to the right-hand end of the resistance wire R.

It is found expedient for reasons later to be brought out to adjust the variable components of the present track circuit to provide proper operation under the wettest condition of the track ballast which is expected to obtain on the particular track circuit. In other words, when the inter-rail leakage current is at substantially its maximum value, these adjustments may be made by 20 positioning the arm 7 of the present resistance adjusting means near the right-hand end of resistance wire R, such as the position shown in Fig. 1, thereby shunting the major part of resistance R from the track circuit, and adjusting 25 the manually variable resistor 6 so that a proper voltage is obtained across the track rails 4.

The proper inter-rail voltage must of course be a predetermined value which reliably picks up 30 and retains the armature of the track relay TR 35 when the track section is unoccupied and yet which permits a train offering a maximum rail shunting resistance to effect the release of the relay armature. The previously described adjustment of the control relay is now made so that 40 with this proper inter-rail voltage across windings 12, the armature 11 assumes an intermediate position wherein contact 14 is midway between contacts 20 and 21.

In order to describe the operation of the automatic regulating means, it will first be considered that the ballast resistance increases due for example to the drying of the ballast between the track rails 4 so that the inter-rail leakage current decreases. This decreases the current flowing through resistances 6 and R and slightly reduces the voltage drop therethrough which raises the inter-rail voltage of the track circuit and likewise the energization of windings 12. This decrease in inter-rail leakage current occurs of 55 course rather slowly but the increase in energization of windings 12 caused thereby soon reaches a sufficient value to upset the rather delicate adjustment of armature 11, that is a slight increase in the magnetic attraction of armature 11 plus 60 the biasing force of spring 16 is sufficient to overcome the force of spring 18 thereby operating contact 14 into engagement with fixed contact 20. The winding 35 of the resistance actuating means is now energized over a circuit from the lower 65 terminal of a suitable battery 13, through contact 14 engaging contact 20, through the winding 35, through contacts 80 and 81 and back to the upper terminal of battery 13.

The energization of winding 35 causes oscillation of armature 58 in the manner previously described which rotates cylinder 40 in a clockwise direction, thereby moving arm 7 farther to the left to insert a greater portion of the resistance wire R into the track circuit. This oscillating operation 75

of armature 58 continues until the resistance inserted into the track circuit by the variable resistor R is increased to a value which reduces the inter-rail potential to its originally adjusted proper value. This proper value of energization of windings 12 obviously restores the balance of the forces acting on armature 11 so that contact 14 again assumes its center position which de-energizes winding 35 to stop the operation of arm 7. Now considering that the conductance of the comparatively dry ballast is increased by rain or the like, it will be clear that an increased ballast leakage current occurs which flows through the increased resistance inserted into the track circuit by variable resistor R. A slight reduction in the inter-rail potential then occurs which reduces the energization of windings 12 to a degree allowing the biasing spring 18 to overcome the reduced magnetic attraction of armature 11 plus the force of spring 16 and thereby cause a movement of the contact 14 into engagement with contact 21. In this case, the armature 11 is responding to a rather small decrement in the energization of windings 12 and the downward force of contact 14 is not sufficient to disengage the pivoted back contact 21 from the fixed contact 24, and an energizing circuit for winding 36 is completed from the lower terminal of battery 13 through contacts 14, 21 and 24, through the winding 36, through contacts 80 and 81 to the upper terminal of battery 13.

This energization of winding 36 now causes armature 59 to oscillate as previously described which rotates the cylinder 40 in a counter-clockwise direction, thereby moving the arm 7 back toward the right hand end of resistance R to decrease the resistance inserted thereby into the track circuit. This oscillation of armature 59 also continues until the resistance has been sufficiently lowered to raise the inter-rail potential to its originally adjusted value thereby restoring the balance of forces acting on armature 11 so that contact 14 is returned to its center position to de-energize winding 36 and stop the operation of arm 7.

In the present system, the value of the resistance inserted into the track circuit by the variable resistor R may be changed much more rapidly than changes in ballast leakage current can possibly occur, and consequently the regulating means will not operate continuously during any very definite change in ballast leakage current, but rather the regulation will occur in short cycles during the total continuous change in ballast resistance. In other words, the time required for a degree of ballast change to occur which is sufficient to move the control relay armature 11 out of its center position is considerably longer than the time required thereafter to actuate the resistance arm 7 to a new position which compensates for this change, and consequently the regulating means never allows ballast changes to cause an increase or a decrease in the energization of windings 12 which exceeds that required to just engage contact 14 with either contact 20 or 21.

It may now be seen that the present track circuit regulating means maintains a constant inter-rail voltage, aside from the small waves of voltage change necessary to effect the control of the regulator, regardless of changes in inter-rail leakage current. The degree of voltage change necessary to initiate operation of the means compensating for such change is determined by the sensitivity of the control relay, and

it seems that the waves caused thereby in the otherwise constant voltage are not detrimental as long as their magnitude does not approach the degree of change necessary to cause operation of the track relay.

The system shown in Fig. 1 also maintains the inter-rail voltage at the proper adjusted value regardless of gradual changes in the terminal voltage of the track battery B such as may be caused by improper charging, abnormal loads or the like. In other words, the adjustment of the biasing force of springs 16 and 18 on the armature 11 provides a definite standard unaffected by variable conditions of the track circuit, to which standard the inter-rail voltage or the energization of windings 12 is related thereby permitting any gradual change in inter-rail voltage regardless of its cause to effect operation of the regulating means. It is further obvious that this definite standard to which the inter-rail voltage is related also determines a fixed point at which the action of the regulating means is stopped thereby preventing the "hunting" or overrunning operation which is inherent to most regulator operation.

It is of course understood that a regulating means of the present type should not operate when a train is occupying the associated track section as such operation might compensate for the reduction in inter-rail voltage effected by the train shunt and hold the armature of the track relay in its energized position thereby defeating the purpose of the track circuit. In the present arrangement, the entrance of a train into the associated track section shunts the track rails 4 to cause an abnormal increase in voltage drop through resistances 8 and R and a consequent decrease in voltage drop through windings 12, which reduces the energization of windings 12 to a much greater degree than the rather slight reduction in energization permitted by the regulator in response to an increase in ballast leakage current. This greater degree of reduction in energization of windings 12 caused by the train shunt greatly reduces the normal attraction of armature 11 thus allowing the force of spring 18 to exert a downward force on the pivoted contact 21 through contact 14 which overcomes the force of spring 22 thereby disengaging contact 21 from contact 24.

In this manner, it will be obvious that the present system differentiates between a reduction in inter-rail voltage due to increased ballast leakage current from a reduction due to a train shunt in a manner to prevent the energization of winding 36 of the regulating means as long as the train shunt exists on the track circuit. In other words, the downward force of armature 11 is determined by the degree of reduction in the energization of windings 12, and as previously described, the reduction in energization of windings 12 due to increased ballast leakage current occurs so slowly that the regulator is able to prevent a reduction in excess of that required to just engage contact 14 with contact 21, but the abrupt reduction in energization of windings 12 due to a train shunt distinguishes therefrom by causing an excessive downward force of armature 11 which is effective to move contact 21 downwardly and open the energizing circuit for winding 36 before the regulator can effectively operate.

In the modified form of the present invention shown in Fig. 3, the track circuit is illustrated in substantially the same form as in Fig. 1, that is,

a track battery B normally supplies current through the manually variable resistor S and the automatically variable resistor R to the track rails 4 and energizes the same track relay TR connected across the other end of rails 4. The arm 7 of the variable resistor R is likewise actuated by the same magnetic means as is illustrated more in detail in Fig. 1 and Fig. 2, this magnetic actuating means being illustrated in a rather diagrammatic manner in Fig. 3 in order to simplify the disclosure.

The means for controlling the operation of the magnetic resistance changing means in Fig. 3, however, comprises a control relay including a polarizing magnetic structure illustrated as a general U-shaped permanent magnet 83, or of course a continuously energized electro-magnet could be used as well. The lower end of a soft iron armature 84 is coupled magnetically and pivotably attached to the center of the permanently magnetized structure 83, while the upper end of armature 84 extends between inwardly extending poles N and S at the upper end of the structure 83. A winding 85 is arranged around the armature 84 and connected across the track rails 4 while a second winding 86 also around the armature 84 is connected in multiple with the manually variable resistor S and the automatically variable resistor R through a second manually adjustable series resistor 87 as shown.

The track circuit is adjusted in Fig. 3 in the same general manner as in Fig. 1, that is, under the wettest ballast condition, the resistance arm 7 is positioned to the righthand end of resistance wire R to insert a minimum resistance into the track circuit, and the manually variable resistor S is adjusted to provide the proper inter-rail voltage which is found to provide reliable track circuit operation. The windings 85 and 86 are oppositely wound around the armature 84, and with this proper inter-rail voltage across winding 85, the manually variable resistor 87 is adjusted so that the energization of winding 86 produces a flux which neutralizes the flux produced by winding 85.

Two compression springs 88 and 89 are provided on opposite sides of the upper end of armature 84, which springs are individually adjusted by respective screws 90 so that when the energization of windings 85 and 86 are balanced to provide equal and opposite flux values, the armature 84 is positioned midway between the poles N and S of the permanently magnetized structure 83. With the armature 84 in this position, a contact 91 attached to the upper end thereof by insulating connectors 92 is positioned midway between a fixed contact 93 and a pivoted contact 94, the contact 94 being arranged in a similar manner to contact 21 in Fig. 1, that is, a compression spring 95 adjustable by screw 96 biases contact 94 against a fixed contact 97.

Considering now that the ballast leakage current decreases in Fig. 3, it will be clear that the voltage drop through resistances S and R decreases thereby slightly decreasing the energization of winding 86 while the inter-rail voltage and the energization of winding 85 slightly increases, thereby upsetting the flux balance in armature 84 and allowing the predominating energization of winding 85 to produce a flux attracting the armature 84 toward pole N of the magnetic structure 83. This operation of armature 84 engages contact 91 with contact 93 which completes an obvious energizing circuit for winding 85 thereby causing oscillation of armature 84

and moving arm 7 toward the left hand end of resistance wire R in the same general manner as described in connection with Fig. 1. This oscillation of armature 84 continues until the resistance inserted into the track circuit by resistance R has been increased to a value which reduces the inter-rail voltage to its normally adjusted value, thereby restoring the balance between the energization of windings 85 and 86 which returns contact 91 to its center position and stops movement of arm 7.

An increase in ballast leakage current however causes an increased voltage drop through resistances S and R which increases the energization of winding 86 but decreases the energization of winding 85, due to a decrease in the inter-rail voltage of the track circuit. This unbalances the energization of windings 85 and 86 and the predominance of winding 86 now produces a flux in the opposite direction than the flux previously considered during the predominance of winding 85, so that in this case, armature 84 is attracted toward pole S of the magnetic structure 83. The contact 91 now engages contact 94 which completes an obvious energizing circuit for winding 86 which causes oscillation of armature 84 and moves the arm 7 back toward the right hand end of resistance wire R. Likewise this oscillation of armature 84 continues until the resistance inserted into the track circuit by resistor R has been decreased to a value which increases the inter-rail voltage to its normal adjusted value, thereby restoring the balance between the energization of windings 85 and 86 to return armature 84 to its center position and stop the movement of arm 7.

The action of the regulating means in response to a train shunt on rails 4 in Fig. 3 is very similar to that described in connection with Fig. 1, that is, the present regulating means prevents the occurrence of a decrease in inter-rail voltage in response to ballast changes which exceeds that required to produce the rather small unbalance in the energization of windings 85 and 86 necessary to just move contact 91 into engagement with contact 94, but the abrupt increase in voltage drop through resistances S and R caused by a train shunt produces an abnormally high degree of energization of winding 86 and an abnormally low degree of energization of winding 85. This produces such an unbalance in the energization of windings 85 and 86 that contact 91 forces contact 94 away from contact 93 and prevents operation of the resistance changing means as long as the train shunt exists on the track circuit.

It will now be clear that each of the illustrated forms of the present invention operates to compensate for small increments or decrements in inter-rail voltage which are due to changes in ballast resistance, but distinguishes therefrom the abrupt decrease in inter-rail voltage caused by a train shunt in a manner to prevent compensation for the voltage decrease across the track rails caused by a train shunt. In this manner, a substantially constant energization of the track relay is maintained when the track section is unoccupied so that the decrease in inter-rail voltage caused by a train shunt, which is prevented from causing operation of the voltage regulating means, can reliably effect the release of the armature of the track relay regardless of ballast conditions.

In making the manual adjustments of the track circuit, it was previously stated that these ad-

justments should be made during the wettest ballast conditions and with the minimum resistance inserted into the track circuit by the automatically variable resistor R. If these adjustments are properly made under the above conditions so that reliable track circuit operation results, it is found that by the use of the present regulating means, a great factor of safety in the response of the track relay to a train shunt is provided as the ballast dries out. In other words, when the track rails are shunted by a train, the voltage drop from rail to rail across the train shunt must be so low a value that the track relay in multiple therewith releases its armature, and as this voltage drop through the shunt is the product of the resistance from one rail to the other through the shunt times the current flowing therethrough, it will be clear that a previously effected increase in resistance of R resulting from the drying out of the track ballast will tolerate a proportional increase in resistance of a track shunt and still provide the low voltage drop thereacross which is required in order to release the armature of the track relay. Therefore, if reliable response of the track relay is obtained during the wettest ballast condition, an even greater assurance of reliable response is provided by the drying out of the ballast.

In Fig. 5 of the accompanying drawings, the above characteristics of the present system are illustrated by curve A which represents the relation of the maximum train shunt resistance which is able to drop the track relay TR in Fig. 1 and Fig. 3 to various track ballast resistance values. In order to better appreciate the advantages of this characteristic of the present invention, a dotted curve A¹ has also been shown which represents the relation of the maximum train shunt resistance which is to drop a track relay in the usual type of track circuit.

In the usual type of track circuit, a constant value of resistance is included in series with the track battery regardless of ballast conditions, and consequently when the ballast dries out, the inter-rail voltage or the voltage across the track shunt increases, thus increasing the shunt current and the voltage drop from rail to rail which is the track relay voltage, thereby requiring a better (lower resistance) track shunt under dry ballast conditions to reduce this rail to rail voltage drop to a value sufficiently low to effect the release of the track relay armature than under wet ballast conditions as will be seen from curve A¹ in Fig. 5. A comparison of curves A and A¹ in Fig. 5 then shows that the most reliable detection of a train shunt is obtained in the usual track circuit under wet ballast conditions and is substantially equal to that provided by the present system under the same conditions, but the reliability of the usual track circuit to detect a train shunt decreases as the ballast dries out as compared to the increased reliability provided by the present system.

An expedient for further improving the operation of a track circuit is shown in Fig. 4 which illustrates a primary-secondary track relay combination, such as shown in the prior application of O. S. Field, Ser. No. 711,397, filed February 15, 1934, which may be substituted for the single track relay TR shown in Fig. 1 and Fig. 3. In Fig. 4, the magnetomotive force required to attract the armature of a primary relay PT from its released position is supplied by the normal track circuit current flowing through all of its windings, but after the armature of relay PT is attracted, a secondary relay ST is picked up

through a front contact 88 which substitutes a substantially equivalent resistance 108 for a portion of the winding of relay PT by a make-before-break contact 88, thereby supplying a reduced magnetomotive force which is sufficient to retain the armature of relay PT in its attracted position.

This track relay combination shown in Fig. 4 may be arranged to drop away at nearly the same energizing voltage that is sufficient to pick up 10 its armature and consequently, it will be clear that when the normal inter-rail voltage is properly adjusted, a rather slight reduction in inter-rail voltage can cause a response of this relay combination. Consequently when the arrangement shown in Fig. 4 is employed in combination with the present voltage regulating means shown in Fig. 1 and Fig. 2, the shunting sensitivity is still further improved so that the relation of the maximum train shunt resistance which is able 20 to drop the relay combination in Fig. 4 to various track ballast resistance values is represented by curve B in Fig. 5. The advantage of employing the voltage regulating means of the present invention in combination with the track relay arrangement of Fig. 4 is graphically illustrated in Fig. 5 by the comparison of this curve B with a dotted curve B¹ which represents the shunting sensitivity of a primary-secondary track relay combination in a conventional track circuit without the present automatic voltage regulating means.

In describing the present invention, attention has only been directed to the illustrated embodiments thereof, without attempting to point out 35 the various alternate or optional features of construction, or the different organizations or combinations that may be employed. For example, the specific oscillating armature means illustrated for moving the resistance arm in either 40 of two directions is only one type of motor means which may be used to advantage in the present system, and it is to be understood that the control means shown in either Fig. 1 or Fig. 3 may be used in a very obvious manner to selectively 45 control the operation and the direction of rotation of a small electric motor of the usual type connected through suitable gears to move the arm 1 of the variable resistor R in the required direction.

In other words, the particular embodiments of the present invention have been selected to facilitate in the disclosure thereof rather than to limit the number of forms which it may assume.

What I claim is:—

1. In combination; a track circuit including a section of railway track, a track relay, a source of energy and a variable resistor all connected in series; a control relay energized in constant proportion to the energization of the track relay; biasing means adjusted to hold the armature of the control relay in a definite center position at a predetermined degree of inter-rail voltage; an actuating means for the variable resistor distinctively controlled by relatively small movements of the control relay armature in each direction from said center position; and means operated by a greater movement of the control relay armature in one direction from said center position for preventing operation of the variable resistor.

2. In a track circuit having a section of track rails, a track relay, a source of energy and a variable resistor all connected in series; the combination of; a reversible electric actuating means

for the variable resistor; a control relay connected across the track rails; biasing means centering the armature of the control relay when a predetermined voltage exists across the track rails; control contact means arranged to selectively control the direction of operation of the electric actuating means in accordance with the direction of a relatively slight movement of the control relay armature from said center position; 10 and a contact means arranged to prevent operation of the electric actuating means by the movement of the armature of the control relay a relatively larger distance from said center position.

3. In a track circuit having an insulated track section, a track battery and a variable resistor all connected in series; the combination of; an electro-magnetic actuating means for the variable resistor; a polarized control relay having an armature biased to a center position; a first winding connected across the rails of the track section and arranged to actuate the armature of the polarized relay in one direction; a second winding connected across the variable resistor and arranged to actuate the armature of the polarized relay in another direction, said armature responding to its bias and the energization of said windings to assume its center position if a predetermined inter-rail voltage exists, contact means distinctively operated by relatively slight movements of the armature of the polarized relay in either direction from its center position in response to variations in ballast resistance to cause operation of the variable resistor actuating means to increase or decrease the resistance of said resistor to restore said armature to said center position; and means operated by a relatively large movement of the armature of the polarized relay in response to shunting of the track circuit by a train for preventing the contact means from causing operation of the variable resistor actuating means.

4. In a track circuit, an insulated track section, a track relay connected across one end of the track section, a track battery connected across the other end of the track section, a variable resistor in series with the track battery to the track section, a polarized relay having one winding connected across the rails of the track section and an oppositely arranged second winding connected across the variable resistor, an armature on the polarized relay biased to a center position and operable in either direction therefrom by a predominance in the energization of one or the other of said windings, an electro-magnetic actuating means for the variable resistor distinctively controlled in accordance with a relatively small movement of said armature in either direction from said center position in response to changes in ballast resistance, and means operated by a larger movement of said armature from said center position in response to shunting of the track circuit by a train for preventing operation of the actuating means.

5. In a track circuit, an insulated track section, a source of energy connected across one end of the track section, a primary track relay connected across the other end of the track section, a secondary track relay controlled by the primary track relay, means operated by the secondary track relay for regulating the magnetomotive force of the primary relay, a rheostat connected in series with the source of energy, electro-magnetic operating means for the rheostat, a control relay connected across the track section, a first contact means on the control relay for control-

ling the electro-magnetic operating means in accordance with smaller changes in energization of the track section than can cause operation of the primary track relay, and a second contact means on the control relay for preventing operation of the electro-magnetic operating means in response to a change in energization of the track section which can cause operation of the primary track relay.

6. In a track circuit for railroads, in combination with an insulated section of track and a source of energy for supplying current to a track relay through the rails of said section, a variable resistor in series with said source of energy, electrically operable means for actuating said resistor to vary its resistance, a control relay connected across the track rails and having an armature moved from a neutral position in one direction by a gradual decrease in inter-rail voltage of the track circuit below a predetermined value as caused by variations in ballast resistance, said armature being moved from such neutral position in the other direction by an increase in inter-rail voltage above such value, contact means co-operating with said armature to govern the operation of said electrically operable means and thereby change the resistance of said resistor to restore said predetermined value of inter-rail voltage, and means actuated by a movement of said armature in response to the sudden and large decrease in inter-rail voltage such as caused by a train shunting the track circuit for preventing operation of said electrically operable means and a change in said resistor.

7. In a track circuit for railroads having the usual track relay and source of current connected across the track rails, a variable resistor in series with said source of current in the connections between such source and the track rails, power means for actuating said resistor to increase or decrease its resistance, a control relay responsive to variations in the inter-rail voltage of said track circuit and having a movable armature, spring means for biasing said armature toward its retracted position with such force that said armature assumes a neutral position for a predetermined inter-rail voltage, means rendered effective upon movement of said armature from its neutral position by an increase or decrease in the inter-rail voltage above and below said predetermined value for governing the operation of said power means to cause either an increase or a decrease in the resistance of said resistor as the case may be until said armature is restored to the neutral position, and means responsive to a relatively quick and large movement of said armature caused by the shunting of the track circuit by a train for preventing operation of said power means and a change of said resistor from the condition existing at the time such train shunt is applied.

8. In a track circuit for railroads having the usual track relay and source of current, a variable resistor in the connections between said source and the track rails for regulating the inter-rail voltage produced by said source under different ballast conditions, a power device operable to increase or decrease the resistance of said resistor at a relatively slow rate, and control means for governing the operation of said power device comprising, a winding connected across the track rails, a spring biased movable element movable in one direction or the other from a neutral position by an increase or decrease in the current in said winding above or below a predetermined value in

response to an increase or decrease in the particular inter-rail voltage which provides the proper operating current for the track relay, contact means co-operating with said movable element to cause operation of said power device and increase or decrease the resistance of said resistor as the case may be until said movable element is restored to its neutral position, and contact means co-operating with said movable element and responsive to a relatively and sudden large movement thereof caused by the shunting of the track circuit by a train for preventing operation of said power device and a change in the condition of said resistor existing when a train enters the track circuit.

9. In a track circuit for railroads having the usual track relay and source of current, a power-operated variable resistance at the feed end of the track circuit in series with said source for regulating the voltage impressed across the track rails from said source, said variable resistance having an operating circuit for an increase in its resistance and another operating circuit for a decrease, a control relay having its winding connected across the track rails at the feed end of the track circuit, said control relay having an armature biased to a neutral position which it assumes for a predetermined value of current in said winding, front and back contacts associated with said armature and respectively closed by its movement from its neutral point in one direction or the other for energizing one or the other of said operating circuits to actuate said variable resistance to increase or decrease its resistance as the case may be to restore said armature to its neutral point, and contact means opened by a relatively quick and large movement of said armature toward its retracted position such as would be produced by the shunting of the track circuit by a train for breaking both of said operating circuits and preventing operation of said resistance device.

10. In a track circuit for railroads, in combination with a source of current for supplying voltage to the track circuit, a variable resistor included in series with said source for regulating the voltage impressed across the track rails from said source, said resistor having an element movable in opposite directions to increase or decrease its resistance, a power device for actuating said element of said resistor, operating circuits for said power device one for each direction of movement of said element, and control means for said power device comprising, a control relay of the tractive armature type having its winding connected across the track rails at the feed end of the track circuit, adjustable spring means tending to move the armature of said relay in opposite directions from the neutral point at which said armature is positioned when a current of a predetermined value flows in said winding, front and back contacts actuated by the movement of said armature from its neutral position for energizing one or the other of said operating circuits to cause a change in the resistance of said resistor to restore the predetermined value of current in said winding, and contact means operated by a relatively sudden and large movement of said armature from its neutral position in response to the shunting of the track circuit by a train for opening both of said operating circuits to prevent a change in said resistor when a train enters the track circuit.

11. In a track circuit for railroads, a power-operated variable resistance in series with the

source of current for the track circuit for regulating the voltage impressed across the track rails from said source, a control relay of the tractive armature type having its winding connected across the track rails at the feed end of the track circuit, an adjustable spring acting to move the armature of said relay toward its retracted position, said armature in response to the force exerted by said spring and an energizing current of a predetermined value in said winding assuming a neutral position, front and back contacts closed by movement of said armature from its neutral position in response to changes in ballast resistance for governing the operation of said variable resistance to increase or decrease its resistance as required to bring the current through said winding to said predetermined value, yieldable biasing means opposing movement of said armature from its attracted position beyond the point at which said back contact is closed, and contact means operated by the movement of said armature in opposition to said biasing means and in response to a large decrease of current in said winding as would be caused by the shunting of the track circuit by a train for rendering the closing of said back contact ineffective to govern said variable resistance.

12. In a track circuit for railroads having the usual track relay and source of current, a power-operated variable resistance device for regulating the voltage impressed across the track rails from said source, a control relay of the tractive armature type having its winding connected across the track rails, adjustable springs acting upon the armature of said relay in opposite directions, said armature in response to the forces exerted by said springs and an energizing current of a predetermined value in said winding assuming a neutral position, a front contact closed by attraction of said armature from its neutral position by an increase in said energizing current for causing operation of said resistance device to increase its resistance until the current through said winding is restored to said predetermined value, a spring biased movable back contact closed by a small movement of said armature from its neutral position toward its retracted position in response to a decrease in the energizing current through said winding for causing operation of said resistance device to decrease its resistance until the current through said winding is restored to said predetermined value, and means associated with said back contact and responsive to a movement thereof in response to a sudden and large decrease in said energizing current as would be caused by the shunting of the track circuit by a train for rendering the closing of said back contact ineffective to govern the operation of said resistance device.

13. In a track circuit for railroads, a regulating device for maintaining substantially constant inter-rail voltage at the feed end of the track circuit irrespective of variations in ballast resistance comprising, a power-operated variable resistance device having operating circuits acting when respectively energized to increase or decrease the resistance of said device gradually, a control relay connected across the track rails at the feed end of the track circuit and including an armature spring biased to a neutral position when a predetermined inter-rail voltage exists, a contact finger carried by said armature for engaging a front contact to close one of said operating circuits when said armature is attracted beyond said neutral position in response to an

inter-rail voltage greater than said predetermined value, a pivoted back contact engaged by said contact finger to close the other of said operating circuits when said armature moves beyond its neutral position in response to a decrease in said inter-rail voltage, an adjustable fixed contact engaging and limiting the movement of said pivoted back contact to a position out of engagement with said contact arm when said armature is in its neutral position, a spring pressing said pivoted back contact against said fixed contact with a predetermined pressure, said pivoted back contact being moved out of engagement with said fixed contact by movement of said armature in response to a sudden and large decrease in inter-rail voltage as would be caused by the shunting of the track circuit for opening said other operating circuit controlled by said back contact.

14. In a track circuit, an insulated track section, a source of energy for the track section, a

variable resistor connected in series with the source of energy to the track section, a magnetic rotor operably connected to the variable resistor, electro-magnetic step-by-step means for selectively imparting intermittent rotation of said rotor in either direction, electro-responsive means connected directly across the track rails and responsive to gradual changes in the inter-rail potential for controlling said electro-magnetic means to adjust said variable resistor to maintain a substantially constant potential across the track rails to compensate for gradual changes in inter-rail resistance, and a contact operated by said electro-responsive means and opened upon a sudden drop in said inter-rail potential due to the entrance of a train into said track section for preventing operation of said electro-magnetic means and adjustment of said variable resistor during the presence of a train in said track section.

OSCAR S. FIELD.
